C. M. SEARL

LAST

Original Filed April 21, 1924

INVENTOR,
Clinton McSearl,
BY *Paulmin Paulmin,*
ATTORNEYS.

UNITED STATES PATENT OFFICE.

CLINTON M. SEARL, OF PORTSMOUTH, OHIO, ASSIGNOR TO THE VULCAN LAST COMPANY, OF PORTSMOUTH, OHIO, A CORPORATION OF OHIO.

LAST.

Original application filed April 21, 1924, Serial No. 707,796. Divided and this application filed November 24, 1924, Serial No. 751,763.

To all whom it may concern:

Be it known that I, CLINTON M. SEARL, a citizen of the United States, residing at Portsmouth, in the county of Scioto and 5 State of Ohio, have invented certain new and useful Improvements in Lasts, of which the following is a specification, reference being had therein to the accompanying drawing.

10 My invention relates to an improvement in lasts, and is particularly directed to lasts of the divided type—that is to say, to that type of last which is divided into two parts, a toe part and a heel part, movable relatively to each other to collapsed and extended positions. The present application is a division of my application filed April 21, 1924, Serial No. 707,796.

15 It is desirable in lasts of this type that the last be capable of being easily collapsed so that it may be removed from a shoe without injury to the lining of the shoe and without stretching the shoe out of place.

20 In lasting a shoe the last is held upside down—that is, with the sole side uppermost—and inasmuch as a great deal of pressure is put on the toe of the last during the lasting operation, this tends to collapse the last, and consequently one of the objects of 25 my invention is the provision of a construction in which the last is capable of withstanding the stresses to which it is subjected during the lasting operation without collapsing, but may be readily collapsed by the operator when desired.

30 In one form of last now in extensive use, the fore part and heel part are attached to each other by a link attached to the fore part and heel part by pins so located relatively that a line drawn through their centers will fall above the axis on which the last parts move when the last is collapsed and below this point or axis when the last is extended.

35 In such a construction, the greater the distance the pins are below the axis of the last when the last is extended, or the greater the distance they are above the axis of the last when the last is collapsed, the more resistance the last will offer to collapse or extension, but this distance is limited inasmuch as the pins must be located in the last body itself, and in the case of wooden lasts the pins must be kept at an appreciable distance

from the bottom or sole face owing to the 55 danger of splitting the last when the same is in use or when being moved from extended position to collapsed position or vice versa.

60 In the present construction I have provided an arrangement for attaching the two last parts to each other whereby an effect is obtained which is as efficient as the lowering of the pins in the above-outlined construction to the danger point, the resistance to collapse or extension offered by my last being very materially increased, without, however, necessitating placing of any pins at a point where they are likely to cause the last to split.

65 It is one of the especial objects of my invention to provide a last in which the last parts are held together under tension and not simply held in expanded or collapsed position under tension.

70 It is a further object of my invention to hold the last parts together by means employing a lever, with the parts constantly under tension.

75 It is a still further object of my invention to hold the parts of the last together under 80 tension with the parts so arranged that the tension will assume its maximum when the parts are either in their fully expanded or fully collapsed position.

85 It is an additional object of my invention to provide the holding together of the parts under tension and to associate therewith a lever, the parts being so arranged that the tension will achieve its maximum at the completely expanded or collapsed position of 90 the last parts. It will be realized that the tension may be created by a variety of means which may be very compressible or expandable, and the details of creating this condition are not essential.

95 It is a further object of my invention to provide such mechanism to hold the parts of the last together under tension that it will not be necessary to have resilient links or resilient anchor pins. Such means are eliminated and the same results are obtained.

100 It is a further object of my invention to provide the holding of such parts together under tension and the increasing of this tension at extreme positions together with 105 means to lock the parts in extended position by such tension means to resist the pressure, tending to collapse the last imposed on the

bottom of the toe member in constructing the shoe thereon until such tension means is overcome by the operator breaking the last.

In the accompanying drawing I have shown a sectional view illustrating my invention.

In the drawing, 1 designates the heel part and 2 the toe part of the last divided as customary by an arcuate cut, as indicated at 3, to provide a bearing about which the last parts move. 4 designates a bearing pin located at the center of the arc 3. Secured on the bearing pin is a triangular plate 5 attached to the heel by a pin 6. The apex of this plate is pivoted by a pin 7 to a link 8 extending into the toe part of the last. 9 designates a second link, one end of which is pivoted on the bearing pin 4 while the forward end extends into the toe part of the last and is pivoted thereto by a pin 10. A short link 11 is pivoted on this pin 10. The link 11 is pivotally attached intermediate its length, as indicated at 12, to the link 8 already referred to. The end of this link 11 engages the under side of a lever 13 pivoted to the toe part of the last, as indicated at 14. Power is applied to the link 13, tending to pivot the same on the pin 14, by a spring 15 lying between the end of this link and a pin 16.

With the parts in the position shown in full lines in the drawings, the force exerted by the spring 15 moves the link 11 downwardly to rotate the plate 5 to the left about the bearing pin 4, thereby shortening the distance between the pins 6 and 10 to hold the last parts in extended position under tension. When the last parts are moved to collapsed position the spring 15 tends to rotate the plate 5 to the right to thereby again shorten the distance between the pins 6 and 10 to hold the last collapsed under tension.

It will be apparent that I have provided a last structure wherein the last parts are held in extended position and in collapsed position under tension, thereby providing a structure which will successfully withstand accidental collapse or extension of the

last parts when the same are in use in the manufacture of shoes. It will be seen also that in my invention I provide a structure in which the force exerted on the last parts to hold the last in extended and in collapsed position is of some magnitude, my improved construction being such, however, that this increase in force is provided without weakening the last. In other words, more power is available for holding the last parts in adjusted position due to my improved structure than is possible in lasts as now manufactured.

It will be seen also that I have provided a last structure wherein the last parts are held in extended position and in collapsed position under greatest tension. In other words, the tension under which the last parts are held to each other when the last is extended or when the last is collapsed, as the case may be, is greater than the tension under which the last parts are held when in an intermediate position.

Having thus fully described my invention, what I claim as new and desire to secure by Letters Patent is:—

In a last of the divided type, the combination of a heel part and a toe part, a bearing pin for said last parts, a plate mounted in the heel part and secured on said bearing pin, a second pin for attaching said plate to the heel part, a link extending from said bearing pin into the toe part of the last, a lever in the toe part of the last, a bearing pin passing through the end of said lever and said link to pivotally connect said link and lever to the toe part of the last, a link extending from the plate in the heel part to a point intermediate the ends of the lever in the toe part, and a spring-actuated lever for applying power to the first mentioned lever in the toe part of the last to maintain the last parts in extended position and in collapsed position under tension.

In testimony whereof, I affix my signature.

CLINTON M. SEARL.
